US0D1001161S

(12) **United States Design Patent** (10) **Patent No.:** **US D1,001,161 S**
(45) **Date of Patent:** **** Oct. 10, 2023**

(54) **SCREED COMPONENT**

- (71) Applicant: **CATERPILLAR PAVING PRODUCTS INC.**, Brooklyn Park, MN (US)
- (72) Inventors: **Michael S. Hemry**, Maple Grove, MN (US); **John E. Jorgensen**, Andover, MN (US); **Monica Agnieszka Orfei**, North St. Paul, MN (US); **Cameron E. Graves**, Summerset, SD (US); **Dustin W. Bryan**, Blaine, MN (US)

- (73) Assignee: **Caterpillar Paving Products Inc.**, Brooklyn Park, MN (US)

(**) Term: **15 Years**

(21) Appl. No.: **29/865,931**

(22) Filed: **Aug. 22, 2022**

Related U.S. Application Data

- (63) Continuation of application No. 29/721,904, filed on Jan. 24, 2020, now Pat. No. Des. 971,968.

(57) **CLAIM**

The ornamental design for a screed component, as shown and described.

DESCRIPTION

FIG. 1 is a front, top, left perspective view of a screed component showing the new design;

FIG. 2 is a rear, bottom, right perspective view thereof;

FIG. 3 is front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is a front, top, left perspective view thereof, in an environment of use.

The broken lines show portions of the screed component that form no part of the claimed design. The broken lines seen in FIG. 9 are for the purpose of showing environmental structure, and form no part of the claimed design.

1 Claim, 9 Drawing Sheets
